UNITED STATES PATENT OFFICE

2,571,923

LIQUID COOLING APPARATUS

Joseph I. Morrison, Lincolnwood, Ill.

Application December 30, 1948, Serial No. 68,198

6 Claims. (Cl. 62—141)

1

This invention relates to cooling systems. More particularly my invention pertains to variable demand cooling systems wherein the cooling fluid is water which is circulating over suitable freezing surfaces and wherein a recirculating refrigerant coil is used.

Cooling systems of the general character indicated above have heretofore been provided for use in the dairy industry and milk receiving stations for cooling milk brought in from dairies or other milk producers. After the milk has been brought to the collecting station it must be cooled from its original temperature to approximately 40° F. In order not to destroy the vitamins contained in the milk, as well as other valuable ingredients, the cooling process must be carried out at a moderate rate in a careful and well regulated manner, as is well understood. One example of a type of cooling system suitable for the cooling of milk by milk collecting stations is that described in my Patent No. 2,448,453, dated August 31, 1948.

One of the objects of my invention is to provide ample heat transfer surface.

A further object is to provide heat transfer surface in the form of projections extending from heat transfer plates, located in the path of flow of the heat transfer liquid, thus bringing additional heat transfer surface into use and causing turbulence of the heat transfer liquid to bring portions of the liquid remote from the heat transfer surface into contact therewith.

Another object of this invention is to provide a means for increasing refrigerating efficiency by eliminating countercurrents of gaseous refrigerant in a downward flowing liquid refrigerant feeder conduit.

Another object of the invention is to provide a refrigerating system which enables a conduit feed of substantially liquid refrigerant to a header in communication with refrigerator pipes.

Yet another object of the invention is to provide an improved cooling system of the character indicated which is compact, flexible, and highly efficient.

Further objects and advantages of the invention will be apparent from the description and claims.

For a more complete understanding of the invention, reference should be had to the drawings in which

Figure 1 is a front elevational view of the apparatus;

Fig. 2 is a sectional view taken along lines 2—2 of Fig. 1;

2

Fig. 3 is an enlarged horizontal sectional view taken on lines 3—3 of Fig. 1, and showing the refrigerating pipes and their common tangential wall;

5 Fig. 4 is a section similar to Fig. 3 but showing less ice formed on the heat transfer element;

Fig. 5 is a view substantially on the line 5—5 of Fig. 1 showing a horizontal cross section of the complete heat transfer apparatus; and

10 Fig. 6 is a perspective view showing the refrigerant content tank and portions of the upper ends of the transfer elements.

Referring to Figs. 1 and 2 of the drawings, the invention as shown is embodied in a tank 10 having a cooling fluid inlet 11 and a cooling fluid outlet 12.

15 Inlet 11 supplies water from an adjacent cooler (not shown) which is of any usual kind and may consist of a chamber containing a series of water cooling coils. Outlet 12 returns the cooled water from the tank 10 to the cooler. Such a cooler is shown at 11 in applicant's Patent No. 2,448,453, dated August 31, 1948. The circulation of the water between the cooling coils and the tank 10 may be brought about by any suitable pumping means.

20 Arranged within the tank are a series of sets of parallel vertical pipes 14 and 14a. Sets of pipes 14 and 14a extend from an upper header 23 to a lower header 22. Each set of pipes 14 has welded to it a common vertical, tangential, heat-conducting wall 15, and each set of pipes 14a has welded thereto a corresponding common, vertical, tangential, heat-conducting wall 17.

25 These sets of vertical pipes are mounted in parallel spaced relation in the tank 10, as indicated in Fig. 2. In order to force the water to circulate over the cooling surfaces of the pipes in sets 14 and 14a, the walls 15 and 17 are of a dimension to fit with their side edges touching the sides of the tank 10 as shown in Figs. 3, 4 and 5.

30 The plates 15 and 17 extend downwardly into engagement with the bottom of the tank as shown in Fig. 2. A vertical partition substantially dividing the tank into halves is provided

35 by a plurality of flow separator plates 18 inserted between the plates 15 and 17 and between these plates and the ends of the tank 10. These separator plates 18 extend upwardly into engagement with the refrigerant container tank 16 and downwardly to a position spaced somewhat from the bottom of the tank as shown in Fig. 2. One side of each of the vertical plates 15 and 17 extends upwardly into engagement with the lower side 40 edge of one of the upper headers 23, the other

side of the plate extending upwardly into engagement with a quadrantial portion of the cylindrical refrigerant-containing tank 16 as shown in Figs. 1 and 6. The edges of these plates 15 and 17 are notched out at 18a to fit around the headers 23.

The flow of the liquid in the tank is in a zigzag path, as indicated by arrows A in Figs. 1, 2 and 5, downwardly from the inlet pipe 11 through the vertical cell-like passages formed by the tank walls and the plates 15, 17 and 18, under one of the separator plates 18, upwardly through a vertical cellular passage or channel, thence over a half length of a header 23, downwardly through a cellular passage, thence under a dividing partition 18, upwardly through the cellular passage, and so on up and down and through the cellular passages, etc., finally reaching the outlet conduit leading back to the cooling tank.

If the heat supplied from the circulating water is less than that absorbed by the refrigerant, ice will be formed on pipes 14 and 14a and walls 15 and 17, and vice versa, if the heat supplied from the water is greater than that absorbed by the refrigerant, the ice will be melted.

The refrigerant container 16 consists of a horizontal cylinder having a surge tank type arrangement for the liquid refrigerant as shown in Fig. 1. The level of the liquid refrigerant at 19 is controlled by the float valve 20. A series of vertical conduits 21 extend from the bottom of the refrigerant container 16 and communicate with the series of bottom headers 22. Bottom headers 22 feed a plurality of vertical pipes 14 and 14a which extend from the bottom header vertically upward to a top header 23. Top header 23 has conduits 24 and 25 at each end which connect it with the upper portion of the refrigerant container 16, this portion being above the level of the liquid refrigerant. The liquid refrigerant container 16 has a conduit 26 for feeding liquid refrigerant to the surge tank from a compressor condenser unit (not shown) and a conduit 27 for conducting vaporized refrigerant back to the compressor. The refrigerant may be any of the commonly used liquefied gases such as ammonia, sulphur dioxide, etc.

The operation of this refrigerating assembly is as follows:

The refrigerating tank 10 is filled with water to a level just above the top edge of the series of upper headers 23 and below the level of the uppermost portions of the upper edges of the plates 15 and 17. Refrigerant is supplied from the compressor at all times, and thus the outer surfaces of the pipes 14 and 14a and of the accompanying walls 15 and 17 are always in a condition to freeze ice, the ice forming on the surfaces in slabs, the thickness depending upon the length of time the system operates and upon the temperature of the milk or other fluid which is being cooled. The degree of ice formation depends upon the amount of heat taken out of the fluid being cooled. If the milk or other fluid does not require a lot of heat removal then ice formation will be accelerated and will continue to build up on the surfaces of the walls 15 and 17 and the pipes 14. The flow of water through the refrigerator and the cooler may be regulated in any suitable manner to assure the prevention of excessive ice formation.

During the cooling operation the liquid refrigerant 28 is flowing through the vertical conduit 21 into the headers 22. The latter then feed the liquid refrigerant into the vertical pipes 14

and 14a, respectively. The surrounding water causes the vaporization of the liquid refrigerant, with the result that the upward flow of refrigerant in the pipes 14 and 14a consists substantially of a major portion of gaseous refrigerant and a minor portion of liquid refrigerant. The gaseous refrigerant then feeds from pipes 14 and 14a into the upper headers 23, and the latter feed at each end by means of the connecting conduits 24 and 25 back to the top of the container 16. Any droplets of liquid refrigerant which may have been carried up through the vertical pipes 14 and 14a are caught by the baffles 29 and drop back into the liquid refrigerant layer 28. The remaining major portion of gaseous refrigerant then flows through the outlet 27 back to the refrigerant compressor and ultimately recirculates back through inlet 26 back to the container 16. The confinement of the refrigerant liquid 28 into the narrow conduit 21 causes the liquid to flow rapidly to the bottom headers 22 with a minimum of gaseous refrigerant formation. By this means the volatilization of the liquid refrigerant into a gas takes place only in the vertical pipes wherein the flow is upward; namely, in pipes 14. Since the flow in pipes 14 is only in one direction there is no conflict of countercurrent fluids with accompanying loss in cooling efficiency.

In order to provide ample heat transfer surface and to cause turbulence for the purpose of bringing substantially all parts of the stream into engagement with the heat transfer surface, I provide a plurality of heat transfer projections 30 mounted on and extending from the heat transfer plates 15 and 17 and extending transversely of the flow of water to provide auxiliary flow of heat between the circulating liquid and the heat transfer devices and to create turbulence in the flow of the congealable liquid. These projections may be in the form of metal tubular elements secured to the heat transfer plates in any suitable manner, as by spot-welding.

In use, if the demand for abstraction of heat in the cooling tank is relatively small, the ice will build up on the heat transfer surfaces of the heat transfer devices somewhat as shown in cross section in Fig. 3, the heat transfer projections causing the formation of mound-like projections of ice 31. When the demand for heat abstraction in the cooling tank is relatively great, the ice formed on the heat transfer device will melt away to somewhat the formation shown in Fig. 4 in which there remains little islets of ice 32 frozen onto the plates and lying between the heat transfer projections.

Further modifications will be apparent to those skilled in the art and it is desired, therefore, that the invention be limited only by the scope of the appended claims.

Having thus described my invention, what I claim and desired to secure by Letters Patent is:

1. An ice-forming and melting apparatus comprising a tank, having an inlet and an outlet, for containing water to be frozen, melted and circulated in a tortuous passageway from the inlet to the outlet, a plurality of juxtaposed, two-faced refrigerant-receiving and heat-transferring devices, each provided with an extensive heat transfer surface on each face thereof and constructed and arranged to receive refrigerant for congealing a liquid on said surfaces, mounted in said tank, said heat transfer surfaces lying in generally parallel planes to provide a plurality of parallel flow spaces, partitions, extending from an intermediate portion of one heat

transfer surface to another, parallel to said flow spaces, to provide additional parallel flow spaces, said surfaces lying in generally vertical planes, the water flow being underneath the lower edges of all said partitions, and a refrigerant container above said partitions with respect to which said partitions have a water-tight connection, for supplying liquid refrigerant to said devices and receiving gasified refrigerant therefrom.

2. An ice-forming and melting apparatus comprising a tank, having an inlet and an outlet, for containing water to be frozen, melted and circulated in a tortuous passageway from the inlet to the outlet, a plurality of juxtaposed, two-faced refrigerant-receiving and heat-transferring devices, each provided with an extensive heat transfer surface on each face thereof and constructed and arranged to receive refrigerant for congealing a liquid on said surfaces, mounted in said tank, said heat transfer surfaces lying in generally parallel planes to provide a plurality of parallel flow spaces, partitions, extending from an intermediate portion of one heat transfer surface to another, parallel to said flow spaces, to provide additional parallel flow spaces, said surfaces lying in generally vertical planes, the water flow being underneath the lower edges of all said partitions, and a refrigerant container above said partitions with respect to which said partitions have a water-tight connection, for supplying liquid refrigerant to said devices and receiving gasified refrigerant therefrom, each of said devices having an upper edge portion on one side of the plane of said partitions extending above the water level in the tank, and an upper edge portion on the other side of said partitions below the water level.

3. An ice-forming and melting apparatus comprising a tank, having an inlet and an outlet, for containing water to be frozen, melted and circulated in a tortuous passageway from the inlet to the outlet, a plurality of juxtaposed, two-faced refrigerant-receiving and heat-transferring devices, each provided with an extensive heat transfer surface on each face thereof and constructed and arranged to receive refrigerant for congealing a liquid on said surfaces, mounted in said tank, said heat transfer surfaces lying in generally parallel planes to provide a plurality of parallel flow spaces, partitions, extending from an intermediate portion of one heat transfer surface to another, parallel to said flow spaces, to provide additional parallel flow spaces, said surfaces lying in generally vertical planes, the water flow being underneath the lower edges of all said partitions, and a refrigerant container above said partitions with respect to which said partitions have a water-tight connection, for supplying liquid refrigerant to said devices and receiving gasified refrigerant therefrom, each of said devices having an upper edge portion on one side of the plane of said partitions extending above the water level in the tank, and an upper edge portion on the other side of said partitions below the water level, said higher edge portions having a water-tight connection with said refrigerant container.

4. An ice-forming and melting apparatus comprising a tank, having an inlet and an outlet, for containing water to be frozen, melted and circulated in a tortuous passageway from the inlet to the outlet, a plurality of juxtaposed, two-faced refrigerant-receiving and heat-transferring devices, each provided with an extensive heat transfer surface on each face thereof and

constructed and arranged to receive refrigerant for congealing a liquid on said surfaces, mounted in said tank, said heat transfer surfaces lying in generally parallel planes to provide a plurality of parallel flow spaces, said devices having provisions for causing the water to flow in one direction along a face of one of said heat transfer devices and in the opposite direction along the opposite face thereof along said flow spaces 5 consecutively from said inlet to said outlet, and water-agitating and ice-anchorage projections secured to and extending from said surfaces into said flow spaces on which ice may form and which will create turbulence in the water flow.

10 5. An ice-forming and melting apparatus comprising a tank, having an inlet and an outlet, for containing water to be frozen, melted and circulated in a tortuous passageway from the inlet to the outlet, a plurality of juxtaposed, two-faced refrigerant-receiving and heat-transferring devices, each provided with an extensive heat transfer surface on each face thereof and constructed and arranged to receive refrigerant for congealing a liquid on said surfaces, mounted in said tank, said heat transfer surfaces lying in generally parallel planes to provide a plurality of parallel flow spaces, said devices having provisions for causing the water to flow in one direction along a face of one of said heat transfer devices and in the opposite direction along the opposite face thereof along said flow spaces 20 consecutively from said inlet to said outlet, and water-agitating and ice-anchorage projections secured to and extending from said surfaces into said flow spaces on which ice may form and which will create turbulence in the water flow.

25 30 35

6. A cooling device comprising a two-faced refrigerant-receiving and heat-transferring device provided with an extensive heat transfer surface on each face thereof lying in a generally vertical plane, and constructed and arranged to receive a refrigerant for cooling said surfaces, a refrigerant container above said device for supplying liquid refrigerant thereto and receiving gasified refrigerant therefrom, said device comprising a lower horizontal header, a conduit extending downwardly from said container below the liquid therein to said lower header for enabling downward flow of liquid refrigerant to said lower header, an upper horizontal header, a set of parallel vertical pipes extending between and affording communication between said headers and enabling upward flow of liquid and gasified refrigerant from said lower header to said upper header, and a conduit extending from each end of said upper header to said container above the liquid level therein to enable the flow of gasified refrigerant from said upper header to the container, said first conduit means comprising a conduit extending through an intermediate portion of said upper header and parallel to said parallel pipes.

JOSEPH I. MORRISON.
